COLORED PICTURE AND DEVICE FOR
PRODUCING SUCH PICTURE

Else Walbinger, Darmstadt, Germany

Application January 16, 1933, Serial No. 652,015
In Germany January 19, 1932

2 Claims. (Cl. 41—34)

5 My invention relates to toys as used for the purpose of producing colored pictures and more specifically consists of a method of producing such pictures without using any dyeing liquid, liquid or pasty colors, colored pencils, pulverized colors, adhesive substances or the like which materials as a rule cause the children to dirty their hands, faces, garments or beddings etc. besides giving them a chance for poisoning.

10 The object of my invention is a new kind of picture in one or more colors on any background, the latter consisting of stencils, while the colored areas of the picture are produced by threading through the slots of said stencils strips of colored sheet material as paper, cloth, metal or the like. These strips are held in position by the edges of said slots.

15 A further object of my invention is to provide and to dispose the slots on said stencils (which form the background of the pictures) in such a way that the slots form on two opposite sides the contours of the respective part or area of the picture to be produced, while the other two sides opposite each other of said area are to be formed by the edges of the strip to be threaded through said slots of the stencil. Thus the edges of said strips and the sides of the colored areas formed thereby respectively have a more or less rectilinear form, but the other sides of the areas as 20 formed by the slots of the stencil may have any curved form as the case may be.

25 The stencils according to the invention as well as the strips to be used may be of any suitable color, material or shape, covered or not with printed matter or illustrations and provided or not with openings or apertures forming parts of the picture to be produced. The strips are preferably provided and prepared so as to have standardized widths corresponding to the similarly 30 standardized dimensions of the slots of the stencils.

35 The subject idea of the invention will result more clearly from the following description of an embodiment of it which forms only one example as many other ways of carrying out my invention may be taken without leaving the limits of it. At all events I wish it to be understood that I do not desire to be limited to the exact details of the construction shown and described in this specification, for obviously modifications will occur to a 40 person skilled in the art.

45 In the accompanying drawings forming a part of this specification, and in which similar reference symbols indicate corresponding parts:

50 Fig. 1 is a plan view of a stencil, the various

strips forming the colored areas being applied thereto;

5 Fig. 2 is a cross sectional view taken on the line II—II of Fig. 1 showing in a more diagrammatical way the slots of the stencil and the strips being threaded therethrough;

Figs. 3, 4 and 5 show in a similar sectional view other forms of said slots;

10 Fig. 6 shows one form of strip material as to be used for producing the pictures aforesaid.

15 As shown by way of example the picture consists of a pine-tree with four distinct rows of branches and with some pine-cones in one of said rows and a squirrel sitting on another. The stencil *a* is shown partly, the remaining portions being cut away. In accordance with the object to be illustrated pairs of slots *b*, *b*; *c*, *c*; *d*, *d*; *e*, *e*; *f*, *f* are disposed on the plane of the stencil *a*, each pair of slots forming two opposite sides of the contours of the portion of the picture included between said slots. Furthermore a special slot *g* of V-like shape is provided at the bottom of the trunk formed by the slots *f*, *f*. *h* is a line printed on the stencil material for indicating the soil near the roots of the tree. A strip *i* is threaded from behind through one of the slots *b* and then back with its free end from the front-side through the other slot *b*. Thus this strip is held in stretched position by the slots *b*, *b*, its edges *k* and *l* respectively forming the remaining two opposite sides of the portion of the picture included between said slots. In quite the same manner the strip *m* is applied to the slots *c*, *c*, the strip *n* to the slots *d*, *d*, the strip *o* to the slots *e*, *e* and the strip *p* to the slots *f*, *f* and *g*. Obviously 25 in practice the proceeding will be such that first the strip *p* and finally the strip *i* will be applied because for sake of a better pictorial effect the slots *c*, *d*, *e* and *f* extend on one side somewhat into the region of the upper-next strip. The upper edges such as *k* of the strips *i*, *m*, *n*, *o* are 30 straight, while the lower ones such as *l* are toothed with respect to their symbolizing the ends of the branches.

35 The various strips *i*, *m*, *n*, *o* may be of equal or different colors or each may be colored in different shadows or colors. The strip *p* may still have another color.

40 It will easily be seen that the lower edge of strip *p* being in register with line *h* extends, between 45 the lower ends of slots *f*, *f*, below the tongue *q* formed by the V-like slot *g*.

50 In order to produce additional effects strip *n* may be provided with openings *r* illustrating pine-cones or the like. An additional strip *x* of a color 55

different from that of strip *n* may be placed below strip *n* and threaded together with the latter through the slots *d*.

In an alternative embodiment of the invention as shown in Fig. 2 additional slots *s*, *s* are provided in the stencil *a* between a pair of slots as for instance *e*, *e*. These slots *s* may illustrate a squirrel or the like. Then by means of a suitable knife corresponding slots *s* are cut into the strip *o* after same having been applied to the stencil *a*, so that the additional strip *t* being colored differently than strip *o* may be threaded through all the slots *s* in a similar way as indicated above.

As it is of some importance that the strips are held securely in accurate position the size and form of the slots as well as the shape of their edges and the adjacent parts of the stencil may be varied according to the materials used. The simplest form of slots is shown in Figs. 2 and 5, the edges *u* being on the same plane and the adjacent parts of the stencil *a* being in line. According to Fig. 3 the portion being adjacent to the slot *v* and being intended to be occupied by the front portion of the strip is somewhat pressed down so that the edges of the slot *v* are directed obliquely with respect to the plane of stencil *a*. In a further alternative form as illustrated by Fig. 4 the edges of slot *w* are somewhat displaced with respect to each other.

Sometimes, however, it may be desirable that a strip threaded through its slots remains slideable in said slots so that the child may shift the strip freely to and fro so that, provided different colors or illustrations are disposed along the length of such strip, said different colors or illustrations will readily appear at will on the front side of the stencil when the strip is shifted to and fro. It is for this reason that in such a case a pinching of the strip within its slots must be avoided.

The strips to be used in producing pictures according to my invention may be prepared and supplied in different standardized widths and forms of their edges and in different colors or patterns and in suitable material or may be printed. Preferably a set of strips of equal or different properties as set forth may be combined to a sheet which is divided by slots or cut lines with different spaces between them and, if desired, of toothed or wave-like or other form, with a margin remaining at one end or both ends

of said slots or cut lines. Thus the necessary strip material may be taken at will from such sheet.

In the accompanying drawings Fig. 6 shows by way of example one form of a set of different strips, as to be used for carrying out my invention, these strips being joint to form a sheet of strips. The sheet *A* is divided by the slots or cuts *B*, *C*, *D* into various strips of different width, but as the cuts do not extend over the whole of said sheet *A*, margins *E* remain which are intended to be the joining element for said strips. While these slots or cuts *B* are straight, the cut *C* is toothed and the cut *D* has a wave-like form. If desired, one of the margins *E* may be dispensed with.

Having described the invention, what is claimed as new and desired to be secured by Letters Patent of the United States is:

1. A picture which consists of a stencil of any suitable material and of oblong strips of any suitable sheet material, each of the latter being threaded through corresponding pairs of slots disposed on said stencil in such a way that one portion of each strip is situated on the face of the stencil between said slots, while the ends of said strips freely extending beyond said slots on the back of the stencil, are covered by the latter, the strips being held in their accurate position by the pinching effect of the edges of said slots.

2. As a device for producing colored pictures, the combination of a stencil provided with slots of standardized dimensions and of a series of elongated strips of correspondingly standardized widths, the said slots being opposed to each other in pairs and being arranged and shaped in such a way that they may form opposed parts of the contours of certain areas or portions of the picture to be produced and being disposed and dimensioned in such a way that one of said strips may fill out the whole length of the corresponding one of said slots when having been threaded therethrough, the edges of said slots being narrow enough to produce a pinching effect upon the said strips, while the said strips being of any color, pattern and shadow and being as wide as to conform to the lengths of the slots, which they are intended to be applied to, and having edges forming the remaining opposite parts of the contour of the said area of the picture.

ELSE WALBINGER.
